INVENTOR:
Moritz Altmann,
BY *John Giedersheim*,
ATTORNEY.

UNITED STATES PATENT OFFICE.

MORITZ ALTMANN, OF CAMDEN, NEW JERSEY.

SUSPENDER-TRIMMING.

SPECIFICATION forming part of Letters Patent No. 255,404, dated March 28, 1882.

Application filed January 25, 1882. (No model.)

To all whom it may concern:

Be it known that I, MORITZ ALTMANN, a citizen of the United States, residing in the city and county of Camden, and State of New Jersey, have invented a new and useful Improvement in Suspender-Trimmings, which improvement is fully set forth in the following specification and accompanying drawings, in which—

10 Figure 1 is a front view of the suspender-trimming embodying my invention. Figs. 2 and 3 are front views of modifications thereof. Fig. 4 is a section in line *x x*, Fig. 1. Fig. 5 is a section in line *y y*, Fig. 2. Fig. 6 is a section in line *z z*, Fig. 3.

15 Similar letters of reference indicate corresponding parts in the several figures.

My invention consists of a suspender having a plate connectible to the buckle and provided with a spring-fastening and with tabs which are pivoted to said plate, the pivot being common to both tabs, and serving also to fasten the tabs to said plate, whereby the plate may be readily attached to the buckle 20 and securely held thereon and removed therefrom and the tabs set properly, regardless of the position of buttons of the waist-band, shape of the wearer, &c.

Referring to the drawings, A represents a 25 plate which is formed with a loop or hook, B, and C represents a suspender-buckle, on the bottom cross-bar or loop, *a*, of which the plate A is hung.

D represents suspender-tabs, which are connected to the plate A by a pivot, *b*, which is passed through the plate and tabs, and properly secured by heading, clinching, &c., whereby the pivot firmly connects the tabs and plate and permits the tabs to turn on the 35 pivot, one tab being shorter than the other.

In order to securely connect the plate A to

the buckle, said plate is formed or provided with a spring tongue or snap, E, which closes the end of the hook and prevents the displacement of the hook. It will be seen that the 45 plate may be readily sprung or snapped on the buckle, thus firmly connecting the buckle and tabs, and by forcing back the tongue, so as to uncover the end thereof, the plate may be removed from the buckle, and the tabs 50 thus disconnected from the buckle without disturbing the webbing or straps. Furthermore, the tabs may be spread relatively to distances between buttons and shifted, so that the long tab is to the right and the short one 55 to the left, or vice versa, and they may thus be adjusted to the position of the buttons, direction of the waistband, shape of the body of the wearer, &c.

I am aware that suspender-trimmings have 60 been provided with attaching-hooks and securing spring-tongues. I am also aware that eyelets and pivots are common in various devices. I am also aware that tabs of suspenders have been pivoted to the plate which depends from the buckle, and the pivot is common to both tabs, wherefore I disclaim said features broadly.

Having thus described my invention, what I claim as new, and desire to secure by Letters 70 Patent, is—

The improved suspender-trimming formed of the plate A, provided with the hook B, the pivot and fastening *b*, and the spring-tongue E, and the tabs D D, said pivot and fastening *b* 75 being common to both tabs, the parts being constructed, combined, and operating substantially as and for the purpose set forth.

MORITZ ALTMANN.
